UNITED STATES PATENT OFFICE.

JOHN F. TROY, OF ALLSTON, MASSACHUSETTS.

RHEOSTAT.

Application filed January 20, 1923. Serial No. 613,812.

My invention relates to rheostats and the like, for controlling electrical circuits, and it has special relation to the so-called filament rheostats for use in radio equipment.

One object of my invention is to provide a rheostat of the above-indicated character which shall be relatively simple and inexpensive in construction and effective and reliable in operation.

More specifically stated, it is an object of my invention to provide a rheostat for the purpose set forth above, embodying a plurality of resistor coils extending in side-by-side relation, and preferably arranged in an arc, together with a movable contact member for bridging the resistor coils.

Viewed from another angle, it is an object of my invention to provide a rheostat of the character in question wherein the movable contact member is adapted to be resiliently engaged by the inner sides of the resistor coils, the contact member thus being wedged along between the coils to provide the desired variation of circuit resistance.

Other objects of my invention will become evident from the detailed description, taken in conjunction with the accompanying drawing, wherein—

Figure 1 is a view, in end elevation of a rheostat constructed in accordance with my present invention, and

Fig. 2 is a side view of the apparatus shown in Fig. 1.

Referring to the drawings, the rheostat here shown comprises a cylindrical supporting member or disk 1 having a plurality of peripheral grooves 2, extending in side-by-side relation, for receiving a plurality of self-supporting resistor coils 3. A movable contact member or arm 4 is supported by a pin or shaft 5 that extends centrally through the disk 1 and terminates, at one end, in a suitable knob or handle 6.

One end of the contact member or arm 4 is bent at right angles and terminates in a V-shaped portion 4a that is located between, and is adapted to be resiliently engaged by, the inner or confronting sides of the two resistor coils 3.

For the purpose of maintaining the coils in position, I utilize a single small screw or bolt 7 that extends through a suitable opening near the periphery of the disk 1. The bolt 7 is adapted to secure in position a pair of metallic terminal members 8, to

which the corresponding confronting ends of the resistor coils are respectively attached to make suitable electrical connections and, at the same time, to secure in position a plurality of suitable insulating members 9 to which the opposite ends of the resistor coils are hooked or otherwise attached. For convenient assembly, a rectangular boss or lug 10 may be provided in conjunction with the terminal members 8, insulating members 9 and the holding bolt 7.

The head of the bolt 7 may also serve as a stop member for the movable arm 4 in its two extreme positions. To hold the contact arm 4 in its "off" position out of contact with the resistor coils themselves, the disk 1 may be provided with a suitable boss or protuberance 11 upon which the V-shaped portion 4a rests in such "off" position.

The operation of my rheostat may be briefly set forth as follows:

Assuming that the contact arm 4 occupies its "off" position, upon movement of the knob 6 the V-shaped portion 4a of the contact arm 4 is resiliently engaged by the inner sides of the resistor coils 3. The V-shaped portion 4a may thus be wedged along between the coils until the limiting position, corresponding to the complete insertion of the two resistor coils, in series relation, in the electrical circuit being controlled, has been reached.

It will be seen that I have thus provided a relatively small and inexpensive rheostat that is particularly adapted for filament control in radio equipment and whereby a delicate and satisfactory control of the filament current may be secured.

I do not wish to be restricted to the specific structural details or arrangement of parts herein set forth, as various modifications thereof may be effected without departing from the spirit and scope of my invention. I desire, therefore, that only such limitations shall be imposed as are indicated in the appended claims.

I claim as my invention:

1. In a rheostat, a pair of coils extending in substantially parallel planes, and a single V-shaped contact member adapted to be wedged along between said coils.

2. A rheostat comprising a supporting member having a plurality of parallel-extending grooves, a plurality of resistor coils disposed in said grooves, and a movable con-

tact member having a portion located between said coils and adapted to engage the same.

3. A rheostat comprising a supporting member having a plurality of parallel-extending peripheral grooves of substantially equal inside diameters, a plurality of resistor coils disposed in said grooves, and a movable contact member adapted to be resiliently engaged by adjacent sides of said coils.

4. A rheostat comprising a supporting member having a plurality of parallel-extending grooves, a plurality of resistor coils disposed in said grooves, and a V-shaped contact member adapted to be wedged along between said coils.

5. In a rheostat, a plurality of resistor coils extending in side-by-side relation, and arranged in arcs of substantially equal diameter and a movable contact member for simultaneously engaging the inner sides of said coils.

6. In a rheostat, a plurality of resistor coils extending in side-by-side relation and arranged in arcs of substantially equal diameter, and a V-shaped contact member adapted to be wedged along between said coils.

7. A rheostat comprising a cylindrical supporting member having a plurality of peripheral grooves, a plurality of resistor coils disposed in said grooves, and a movable contact member for simultaneously engaging the confronting sides of said coils.

8. A rheostat comprising a cylindrical supporting member having a plurality of peripheral grooves, a plurality of resistor coils disposed in said grooves, and a movable contact member adapted to be resiliently engaged by the inner sides of said coils.

9. A rheostat comprising a cylindrical supporting member having a plurality of peripheral grooves, a plurality of resistor coils disposed in said grooves, and a V-shaped contact member adapted to be wedged along between said coils.

10. A rheostat comprising a cylindrical supporting member having a plurality of peripheral grooves, a plurality of resistor

coils disposed in said grooves, a plurality of conducting members secured to one set of ends of said coils, a plurality of insulating members secured to the other set of ends, and single means for securing said conducting members and said insulating members in position.

11. A rheostat comprising a cylindrical supporting member having a plurality of peripheral grooves, a plurality of resistor coils disposed in said grooves, a rotatable pin extending axially through said supporting member, and a movable contact arm having one end secured to said pin and having its other end adapted to engage the inner sides of said coils.

12. A rheostat comprising a cylindrical supporting member having a plurality of peripheral grooves, a plurality of resistor coils disposed in said grooves, a plurality of conducting members secured to one set of ends of said coils, a plurality of insulating members secured to the other set of ends, single means for securing said conducting members and said insulating members in position, and a movable contact arm having one end secured to said pin and having its other end adapted to engage the inner sides of said coils.

13. In a rheostat, a plurality of resistor coils arranged in the form of a cylinder and having substantially the same outside and inside diameters and extending in side-by-side relation, and single contact means for concurrently engaging the inner sides of said coils.

14. In a rheostat, a plurality of annularly disposed helices of conducting material having substantially the same diameter and extending in side-by-side relation, single contact means for concurrently engaging confronting sides of said coils, and means for relatively moving said helices and said contact means.

In testimony whereof, I have hereunto subscribed my name this 10th day of January, 1923.

JOHN F. TROY.
